UNITED STATES PATENT OFFICE.

CLARK P. TILLINGHAST AND GEORGE F. ALBRO, OF PROVIDENCE, RHODE ISLAND.

DESIGN FOR A PIN.

SPECIFICATION forming part of Design No. 26,058, dated September 22, 1896.

Application filed August 5, 1896. Serial No. 601,818. Term of patent 3½ years.

To all whom it may concern:

Be it known that we, CLARK P. TILLINGHAST and GEORGE F. ALBRO, of Providence, in the county of Providence and State of Rhode Island, have invented and produced a certain new and ornamental Design for Jewelry Pins and Brooches; and we do hereby declare that the following is a full, clear, and exact description thereof, reference being had to the accompanying drawing, and to the letters of reference marked thereon, which forms a part of this specification.

The drawing shows a front elevation of the design and pin.

The leading feature of our design consists in a scroll or fillet arranged in an arched

form on the upper end of the pin, surmounted by an arm bent in a position to strike and holding a sword, and an ornamental loop attached to the center of the lower side of the scroll.

What we claim is—

The design for a jewelry pin or brooch substantially as herein shown and described.

In testimony whereof we have hereunto set our hands this 3d day of August, A. D. 1896.

CLARK P. TILLINGHAST.
GEORGE F. ALBRO.

In presence of—

EDW. H. TILLINGHAST,
BENJ. ARNOLD.
